OUTLET BOX

Filed June 8, 1925

INVENTOR

FREDERICK B. ADAM,

by Clegg & Schramberg ATTORNEYS

UNITED STATES PATENT OFFICE

FREDERICK B. ADAM, OF ST. LOUIS, MISSOURI, ASSIGNOR TO FRANK ADAM ELECTRIC CO., OF ST. LOUIS, MISSOURI, A CORPORATION OF MISSOURI

OUTLET BOX

Application filed June 8, 1925. Serial No. 35,735.

My invention relates to improvements in outlet boxes for installation in wall cavities and more particularly to outlet boxes having angularly adjustable elements constituting 5 supports for cover, wall, or finish plates and hangers for fans or the like.

Ordinarily outlet boxes adapted for the hanging of a fan, or the like, therefrom, consist of a box, a cover plate, securable to the 10 box, and a stud, or hanger carried by the cover plate for the support of the fan.

My object is to construct a box, especially designed for installation in a wall opening or cavity, provided with a device, having 15 support upon an element of the box, means for its angular and distance adjustment relative to the box and arranged to support a fan, or the like, and to which a cover, or finish-plate, may be detachably secured.

20 My improvements consist in the novel construction, arrangement and combination of parts as hereinafter fully, clearly and concisely described, definitely pointed out in my claims and illustrated by the accompanying 25 drawing in which:—

Fig. 1 is a vertical sectional elevation of an outlet box, embodying my improvements, as installed in a wall cavity, showing fragmentarily a fan-base as hung therefrom; and 30 Fig. 2 is a front elevation with a portion of the cover-plate broken away.

Referring by numerals to the drawing, 3 designates the outlet box, comprising essentially elements forming a fire-proof lining 35 for a wall cavity and a lug, or seat 4, arranged, by preference, in each corner of the box and near its open front side. A plate 5, contoured to fit within the box 3, whose one (lower) margin rests upon the box and 40 whose remaining margins are clear, or spaced from the box, is arranged, as by the perforations 6, for attachment to the lugs 4 by means such as the screws 7. To provide for angular adjustments or trueing of the 45 plate 5, relative to the box, the recited perforations are formed as slots, as shown in Fig. 2.

Formed in the angularly adjustable plate 5 is an internally threaded opening 8 arranged for the reception of a hanger 9,

which projects outwardly from the box to provide for the support of a fan, or the like. As shown in the drawing, this hanger may be inserted in the recited opening either from the front or the back of the plate. By 55 preference, and as shown, the opening 8 is burred, or flanged, whereby to increase the bearing for the hanger, and by further preference the hanger is a screw, or bolt having a threaded shank. The plate 5 is further 60 provided with a threaded seat 10 for the reception of a screw 11 which co-acts with hanger 9 for the securing of a cover or 65 finish plate 12, to the adjustable plate 5, and the plate 12 is perforated, as at 13, for the extension therethrough of the hanger 9.

Obviously the plate 5, and hence the cover 12, may be selectively allocated with respect to an installed outlet box, whereby a cover, or finish plate, may be properly installed and secured to an improperly installed outlet box, and by preference the screw 11 and hanger 9 are made relatively long whereby to reach the plate 5 in boxes which are inset from the wall surface. Obviously, further, by reason of the hanger device being carried on an element rested upon the fixed outlet box the weight of an article, such as a fan, is borne by the box, instead of the relatively light cover, or finish plate 80 as is now the practice.

I claim:—

1. Means for demountably supporting, and supplying an electric appliance, said means including an outlet box, a mounting 85 plate disposed within and directly supported by a base portion of the box, means for angularly adjusting within a given plane, and securing said plate relative to the box, an appliance supporting element 90 extending through said plate and extending forwardly of the box, and a cover plate supported by said mounting plate.

2. In a combined outlet and support for a demountable electric appliance, an outlet 95 box, a plate supported directly by engagement of its edge with the lowermost portion of the box, means for angularly adjusting the plate within its structural plane, and securing the plate relative to the box, a re- 100

movable and replaceable appliance hanger bolt carried by said plate, and extending outwardly beyond the box, a cover plate and means for detachably securing the cover plate to the first mentioned plate.

3. In a combined outlet and fan hanger device, an outlet box, a plate inside of the box, having marginal bearing engagement with the lower wall portion of the box, a cover, means entirely within the box including corner supports and holding members engaging the supports, said means adapted for angularly adjusting said plate within a given plane, relative to the box, and means for securing the cover to said plate.

4. In an outlet and fan hanger device, the combination of an outlet box, a cover plate therefor, a perforated adjusting plate positioned in the box, an arcuate, marginal rest portion on said plate, in engagement with the lowermost wall portion of the box, a hanger bolt extending through the perforation in the adjusting plate, securing members disposed near the inside corners of the box, forming a seat for the adjusting plate, and holding means engaging the adjusting plate and securing members for securing the cover plate to the box at selective variable angles relative to one wall portion of the box.

5. An outlet fixture and support for a demountable electric appliance, including, in combination, an outlet box, a flat plate entirely within the box, and having an arcuate lower edge engaging, in rockable relation, the lowermost enclosing wall of the box, means within the box permitting the angular adjustment or rocking of said plate, and for securing the plate in adjusted position, said means including a plurality of box corner supports, forming seats for said flat plate, substantially parallel to and spaced from the rear wall of the box, and screws extending through the flat plate into said seats, the plate having slotted apertures for said screws; a cover plate, and an element detachably secured to the said flat plate and comprising a support for the cover plate and for a demountable appliance associated with the box.

FREDERICK B. ADAM.
